UNITED STATES PATENT OFFICE.

EDWARD KENDALL, OF CAMBRIDGEPORT, MASSACHUSETTS.

FEED-WATER HEATER.

SPECIFICATION forming part of Letters Patent No. 269,586, dated December 26, 1882.

Application filed August 30, 1882. (No model.)

To all whom it may concern:

Be it known that I, EDWARD KENDALL, of Cambridgeport, in the county of Middlesex and State of Massachusetts, have invented certain new and useful Improvements in Feed-Water Heaters, of which the following, taken in connection with the accompanying drawings, is a specification.

My invention relates to the construction and arrangement of the heater-pipes and the means of controlling the flow of the water through the same; and it consists in the combination of a series of clusters of small pipes extending across the smoke-flue leading from the boiler to the chimney, and each having a portion of its length bent at right angles to its main portion, and two series of larger pipes located outside of said smoke-flue and each receiving one end of all of the small pipes in one of the clusters, as will be more fully described.

It further consists in the combination, with said series of clusters of small pipes and the said series of larger pipes, of a series of cocks or gates, by means of which the flow of water through the several clusters of pipes may be regulated.

It further consists in the combination, with the smoke-flue of a boiler, the series of clusters of small pipes, and the series of larger pipes, of a reservoir located above the boilers, connected at one end to one end of the circuit of heating-pipes and at the other end to the opposite end of the circuit of the heating-pipes and to the boiler in such a manner that heated water may be supplied to the boiler from said reservoir, or, when not required in the boiler, the water may circulate from said reservoir through the heating-pipes and back to the reservoir.

It further consists in the combination, with a heater composed of a series of clusters of small pipes and two series of larger pipes, of a reservoir connected therewith and provided with one or more sediment-collecting pockets, pendent deflectors, bridges, and blow-off cocks, as will be hereinafter more fully described in connection with the description of the drawings, and particularly set forth in the claims.

Figure 1 of the drawings is a front elevation of a pair of boilers with my improved heater and reservoir applied thereto, a portion of the

brick wall of the smoke-flue being broken away to show the several clusters of small pipes. Fig. 2 is a plan of the same with the metal covering-plate of the smoke-flue removed and the rear portions of the boilers broken away. Fig. 55 3 is a longitudinal section of the reservoir, and Fig. 4 is an enlarged elevation of one of the large pipes which connect the clusters of small pipes.

A and A' are two boilers, to be supplied 60 with water and inclosed in suitable brick setting, B.

C is a cylindrical tank or reservoir, supported by the brick piers D D in a position above the boilers, and may be located over the front end 65 of the boilers, as shown, or at any other convenient point.

E is a flue through which the hot gases and other products of combustion pass on their way from the boilers to the chimney, and is 70 shown in the drawings as being composed of two brick side walls, E' E', and a top and bottom of plate-iron, as indicated by letters a and a', respectively. A series of clusters of small pipes, b b, extend vertically across said flue 75 and through the top and bottom plates thereof, each pipe in every cluster being connected at one end by means of a quarter-turn with a short horizontal pipe, c, which pipes are inserted in and communicate with the interior 80 of the larger pipes, F or F', according as they are above or below the flue E. The clusters of small horizontal pipes c are arranged alternately above and below the flue E, as shown in Fig. 1, and the ends of the pipes b b opposite to said pipes c c are inserted in and communicate with the interior of the large pipes 85 G or G', arranged respectively above and below the flue E, as shown.

The pipes F are each connected with one of 90 the pipes G by means of a U-shaped pipe, d, and each of the pipes F' is in like manner connected to one of the pipes G'. The opposite ends of the pipes F and F' are connected through the pipes e and f, respectively, to the 95 pipes H and I, as shown in Fig. 1.

The pipes e and f are each provided with a stop-cock or gate, e' or f', and a stop-cock or gate, g or h, is inserted in the connecting-pipe between each pair of pipes F G and F' G', as 100

shown in Figs. 1 and 2. The pipe H communicates by one end with the interior of the reservoir C at one end, near its top, and by its other end with the supply-pipe J, and is provided with the stop-cocks or gates i, j, and k, as shown. The pipe I communicates by one end with the interior of the reservoir C at or near the end thereof, opposite to the pipe H, and by its other end with the supply-pipe J, and is provided with the stop-cocks or gates l and m, as shown.

Branch pipes n and o lead from the pipe I to and communicate with the water-spaces of the boilers A and A', respectively, and are provided with the stop-cocks or gates n' and o', respectively, as shown in Fig. 1. The water-supply-pipe J leads to and communicates with a suitable pump or other means of supplying water under pressure. (Not shown.)

20 The reservoir C is provided with one or more sediment-collecting pockets, p, each provided with a suitable discharge-pipe, q, and blow-off cock q', as a means of discharging the sediment that may accumulate in the pockets p.

25 One or more deflectors, in the form of pendant partitions r, are arranged directly above the sediment-pockets p, and serve to compel the water discharged into the reservoir through pipe H to take a downward course at or near the sediment-pockets in order to pass to the other end of the reservoir and be discharged therefrom through the pipe I.

30 One or more other deflectors, s, in the form of partial bulk-heads, rise from the bottom of the reservoir to a point near the center thereof, and serve to compel the water, after it has passed beneath the deflector r, to take an upward course again, thus creating a certain degree of agitation of the water, which, by virtue of the greater weight of the sediment, facilitates the deposit of said sediment in the pockets p p.

L is a safety-valve mounted upon the reservoir C, to regulate the pressure therein.

45 The operation of my improved feed-water heater is as follows: If it is desired to charge the reservoir C with hot water, to be used at will for supplying water to the boilers A and A', or if it is desired to keep up the supply of water in the reservoir, after it has been filled, to replace that drawn out to feed the boilers, the stop-cocks g and h, the left-hand stop-cock, e', and the right-hand stop-cock, f', are opened, while all the remaining stop-cocks remain closed. If, now, the pump be set in operation, or the water be let into the supply-pipe from any suitable head, the water will be made to circulate through each of the clusters of small pipes b b, through the pipes F F' G G' d, the

55 left-hand pipe, e, stop-cock, e', and the pipe H, and be discharged into the reservoir C, the body of water being subdivided into a large number of small columns each time that it passes across the flue E, where it is exposed to the action of the hot gases passing through said flue, by which means the water is much more effectually heated than it otherwise

could be. If it is desired to supply water to the boiler A, the stop-cock n' is opened, and if it is desired to feed water to the boiler A' the 70 stop-cock o' is opened. At times when the boilers are full, and as a consequence no water is needed to be supplied thereto, the cocks n' and o' are closed and the cocks l, m, e', and f' are opened, and the supply from the pump or other head is shut off, when a circulation of water will be kept up through the heater by the cooler water in the bottom of the reservoir C descending through the pipe I, passing through the several clusters of small tubes in the flue E 80 and through a portion of the pipe H, and being discharged thence into the upper part of the reservoir again.

In constructing my improved feed-water heater care has been taken to keep all of the 85 joints in the pipes as well as all of the stop-cocks or gates outside of the flue E, thereby rendering them easy of access for repairs or inspection.

Another advantage of my arrangement is 90 that if an accident happens to one section of the heater the whole heater does not have to be cut out of the circulation and cold water be fed into the boilers, as is the case, so far as I know, with the heaters now in use; but by the 95 proper use of the stop-cocks provided the damaged section of the heater may be cut out while the circulation is maintained intact through the other sections of the heater—as, for instance, if some one or more tubes in the right-hand cluster give out by closing the right-hand cocks, f', f', and h, opening the cock k and the second cock, e', from the right, the water from the supply-pipe J will pass through the vertical portion of pipe H, and along its horizontal 105 part to the second branch pipe, e, through it and its cock e', and from thence will circulate through that portion of the heater lying between said pipe e and the reservoir C.

Another advantage of my improved heater 110 is that the sediment contained in the feed-water will be collected in the pockets p, and may be blown off without being carried into the boilers to be deposited in the form of scale upon the shell of the boiler to its injury.

115 What I claim as new, and desire to secure by Letters Patent of the United States, is—

1. In a feed-water heater, a series of clusters of small pipes extending across the smoke-flue leading from the boiler to the chimney and having a portion of their length bent at right angles to the main portion, and two series of larger pipes located outside of the flue and each receiving one end of all the small pipes in one of the clusters, substantially as described.

2. The combination, in a feed-water heater, of a series of clusters of small pipes extending across the smoke-flue leading from the boiler to the chimney, two series of larger 130 pipes located outside of said flue and each receiving one end of all the small pipes in one of the clusters, and two series or sets of stop-cocks or gates arranged to regulate the flow

of water through the several clusters of small pipes, substantially as described.

3. The combination of the series of clusters of small pipes *b c*, the two series of larger pipes, *F G* and *F' G'*, the reservoir *C*, and suitable pipes connecting the opposite ends of said reservoir to the opposite ends of the heater and one end thereof to the boiler, substantially as described.

10 4. The combination of the series of clusters of small pipes *b c*, the two series of larger pipes, *F G* and *F' G'*, the reservoir *C*, provided with one or more sediment-collecting pockets, *p*, and one or more pendent deflectors, *r*, and 15 suitable pipes connecting the opposite ends of the reservoir to the opposite end of the heater and one end thereof to the boiler, substantially as described.

5. The combination, with a steam-boiler, of 20 the series of clusters of small pipes *b c*, the two series of larger pipes, *F G* and *F' G'*, the reservoir *C*, provided with one or more sediment-collecting pockets, *p*, one or more pend-

ent deflectors, *r*, and one or more blow-off cocks, and suitable pipes connecting the opposite ends of said reservoir to the opposite ends of the heater and one end thereof to the boiler, substantially as described.

6. The combination of the series of clusters of small pipes *b c*, the two series of larger pipes, *F G* and *F' G'*, the reservoir *C*, provided with one or more sediment-collecting pockets, *p*, one or more pendent deflectors, *r*, one or more bridges, *s*, and one or more blow-off cocks, and pipes connecting said reservoir to the heater 35 and for discharging the water therefrom, substantially as described.

In testimony whereof I have signed my name to this specification, in the presence of two subscribing witnesses, on this 26th day of August, 40 A. D. 1882.

EDWARD KENDALL.
